CLAIM

We claim the ornamental design for a power module, as shown and described.

DESCRIPTION

FIG. 1 is a right front side perspective view of the power module;

FIG. 2 is a top side view of the power module shown in FIG. 1;

FIG. 3 is a bottom side view of the power module shown in FIG. 1;

FIG. 4 is a right side view of the power module shown in FIG. 1;

FIG. 5 is a left side view of the power module shown in FIG. 1;

FIG. 6 is a front side view of the power module shown in FIG. 1; and,

FIG. 7 is a back side view of the power module shown in FIG. 1.

In the drawings, the claimed design is defined by the shaded surfaces; broken lines immediately adjacent shaded surfaces represent boundaries of the claim and form no part thereof; all other broken lines depict unclaimed environmental subject matter and form no part of the claim.

1 Claim, 7 Drawing Sheets
